UNITED STATES PATENT OFFICE.

WILLIAM GORMAN, OF PITTSBURG, PENNSYLVANIA.

HEATING-FURNACE.

SPECIFICATION forming part of Letters Patent No. 702,722, dated June 17, 1902.

Application filed November 21, 1901. Serial No. 83,131. (No model.)

To all whom it may concern:

Be it known that I, WILLIAM GORMAN, a citizen of the United States of America, residing at Pittsburgh, in the county of Allegheny and State of Pennsylvania, have invented certain new and useful Improvements in Heating-Furnaces, of which the following is a specification, reference being had therein to the accompanying drawings.

10 This invention relates to certain new and useful improvements in heating-furnaces, and relates more particularly to that class where-in natural and artificial gas are employed for fuel.

15 The object of the present invention is to provide a heater that will be extremely simple in its construction, strong, durable, and comparatively inexpensive to manufacture; furthermore, one that may be readily taken 20 apart and set up in proper position.

With the above and other objects in view the invention consists in the novel combination and arrangement of parts to be herein-after more fully described, and specifically 25 pointed out in the claims.

In describing the invention in detail reference is had to the accompanying drawings, forming a part of this specification, and where-in like numerals of reference indicate corresponding parts throughout the several views, 30 in which—

Figure 1 is a side elevation of my improved furnace. Fig. 2 is a vertical sectional view thereof. Fig. 3 is a top plan view of the same. 35 Fig. 4 is a vertical sectional view of a portion of the outer casing, the combustion-chamber, radiator-pipe, and hot-air pipes. Fig. 5 is a top plan view of the removable base-plate. Fig. 6 is a top plan view of the furnace as 40 shown in Figs. 1 and 2 of the drawings, with the head of the casing removed therefrom. Fig. 7 is an enlarged perspective view of the burner. Fig. 8 is a similar view of the grate or basket for the reception of the refractory 45 material.

In the drawings the reference-numeral 1 indicates a suitable base, having an annular recess 2 formed therein on its upper face to receive the annular shell 3, which is seated 50 therein, said annular shell having communicating therewith the cold-air-inlet pipe 4.

The reference-numeral 5 represents a re-

movable base-plate, having formed therein near its outer end an annular recess 6 for the reception of the outer casing 7, said casing 55 being provided with a water-receptacle 8, extending into the casing 7, said water-receptacle being provided with a hinged cover 9, attached at 10 to the outer face of the casing 7. The portion extending into the casing 7 60 has an open top to allow the evaporation of the water.

The reference-numeral 11 represents a hood carrying an inwardly - extending annular flange 12, forming an annular space between 65 said flange and the outer wall of said hood, in which is seated the upper end of the outer casing 7. The said hood carries an inverted-cone-shaped top 14, which extends into the hood proper and forms a spreader or deflector, 70 the inner walls of which are in close proximity to the hot-air outlets 15, formed in the hood, said hot-air outlets communicating with the distributing-pipes 16, which lead to the different apartments to be heated. 75

The reference-numeral 17 represents a gas-supply pipe extending into the cone-shaped mixer 18, which is formed at the lower end of the burner 19, said burner being preferably rectangular in form and having inclined sides 80 terminating in the flange 20, said flange engaging the under face of the removable base 5, said base-plate 5 having a central opening 21 formed therein, through which the upper end of the burner extends. The said burner 85 19 has formed therein a series of openings 22, leading into the combustion-chamber 23. At the upper end of said burner are inwardly-extending walls 24, which likewise form the deflector, as will be readily understood. 90

The reference-numeral 25 represents a grate or basket, which is preferably rectangular in form and is adapted to receive the refractory material 26, said grate or basket being rigidly secured in any suitable manner to the 95 upper face of the burner. The said combustion-chamber 23 is formed by the cylindrical inner casing 27, said cylindrical inner casing being seated at its lower end in the annular recess 28, formed in the upper face of the removable base-plate, the said annular recess being in close proximity to the central opening 21 and extending upwardly into the radiating-pipe 29, the upper end of said cylinder 100

drical casing being provided with a deflector 30. The opening 31 is formed in the upper portion of the cylindrical casing 27 to communicate with the radiator-pipe 29, said pipe 5 extending through the outer casing 7, as shown at 32, and leading to the flue or chimney. (Not shown in the drawings.)

The reference-numerals 33 indicate air-pipes, which are seated between the flanges 10 34, formed on the upper face of the removable base-plate, said air-pipes communicating with the series of openings 35, formed in the removable base-plate and communicating with the cold-air inlet. These air-pipes 33 are 15 of greater diameter at their lower ends than at their upper ends, and their walls gradually extend atan angle inwardly in order to check the direct draft and retard the currents of air to permit the same to be heated in their 20 passage through the heater.

The reference-numeral 36 represents a cylindrical opening formed in the outer casing, extending through one of the air-pipes and into the combustion-chamber for the purpose 25 of forming a hand-hole to permit the ignition of the gas, this cylindrical opening 36 being provided with a door 37, which is hinged at 38, said opening being normally closed to prevent the heat from escaping through this 30 outlet.

The operation of my improved device is as follows: We will assume that the gas has been ignited, which will heat the grate or basket retaining the refractory material, 35 which will serve to retain the heat and assist in producing a larger number of units of heat, it being a well-known principle of physics that the heat will concentrate, and as the latter rises the deflector 30 will serve to deflect the 40 heat toward the inner walls of the cylindrical casing forming the combustion-chamber. The burned gases will then escape by the way of the opening 31, and by means of the circuitous course of the radiating-pipe 29 the draft 45 will be checked, and the pipe 29 will then serve a double purpose of conducting the burner gases and fumes and, furthermore, produce a larger heating-surface than could otherwise be obtained. By reason of the peculiar construction of the air-pipes 33 the air 50 will be thoroughly heated from the combustion-chamber. The heated air will then be conveyed through the conducting-pipes to the various compartments.

55 It will be noted that by reason of the deflectors 14, 24, and 30 the heat will not only be deflected and an equal distribution of the same obtained, but will also be baffled, thereby obtaining advantages that will be readily 60 apparent in this class of inventions.

It will be noted that various changes may be made in the details of construction without departing from the general spirit of my invention.

Having fully described my invention, what 65 I claim as new, and desire to secure by Letters Patent, is—

1. In a heater, the combination of a base having formed therein an annular recess, a cylindrical casing seated in said recess having formed therein an air-inlet, a removable base arranged above said casing having formed therein a series of openings, a burner secured in said removable base, an outer casing secured above said casing, a water-receptacle 70 extending into said outer casing, an inner casing forming a combustion-chamber, a deflector arranged at the upper end of said inner casing, a radiating-pipe communicating with said combustion-chamber arranged 75 above said inner casing, a removable hood, a deflector secured at the upper end of said hood, a series of distributing-pipes communicating with said hood, all parts being arranged substantially as described. 80

2. In a heater, the combination of an inner and outer casing, a series of tapering air-pipes arranged around said inner casing, a burner, a grate or basket secured to the upper face of said burner, refractory material 90 arranged in said grate or basket, a deflector arranged at the upper end of said inner casing, a radiating-pipe communicating with said combustion-chamber, a suitable hood, and a series of distributing-pipes extending 95 from said hood, substantially as described.

3. In a heater, the combination of a suitable support having formed therein an annular recess, an annular casing seated in said recess having formed therein an air-opening, 100 a removable base-plate arranged to support said casing having formed therein a series of openings, a burner arranged in said base-plate, a deflector secured in said burner, a grate having arranged therein refractory material secured above said burner, an inner and outer casing, a series of tapering air-pipes arranged around said inner casing, a deflector secured to the upper end of said inner casing, a radiating-pipe secured upon 110 said inner casing and communicating therewith, a hood carrying a deflector, and a series of distributing-pipes connected to said hood, substantially as described. 115

In testimony whereof I affix my signature in the presence of two witnesses.

WILLIAM GORMAN.
